APPARATUS FOR TREATING CLOTH

Henry A. Woodhead, Graniteville, S. C.

Application November 24, 1934, Serial No. 754,576

15 Claims. (Cl. 26—18.6)

This application is a continuation in part of my copending application Serial No. 674,495 filed June 6, 1933, now Patent No. 1,982,720 dated December 4, 1934, and relates to apparatus for preshrinking cloth for the purpose of substantially eliminating shrinkage in both weft and warp in subsequent laundering operations.

There have been several attempts to obtain a satisfactory process for producing a preshrunk cloth. These methods of preshrinking consisted, for example, in wetting the cloth and permitting shrinkage to take place while the cloth was hung in loops from suitable frames; in imposing a certain crinkle on one set of yarns by pulling out the opposite set of yarns by means of a tentering frame or similar apparatus; or in affixing the cloth to the surface of a relatively thick carrier blanket while the blanket is flexed to a convex position and subsequently flexing the blanket to a concave position to diminish its surface and effect a change in the superficial dimensions of the web warpwise. However, all of these various methods have entailed numerous disadvantages both in the operation of the apparatus and in the characteristics imposed upon the fabric as is more fully discussed in my earlier application.

The speed of the prior art apparatus, for example, was found to be limited thus producing preshrunk fabric at only a relatively low rate.

Another important disadvantage of the prior art shrinking processes is that they are incapable of carrying out the steps of sizing, shrinking, and finishing in one continuous unitary operation, but rather the fabric must be sized, then dried, then again moistened and shrunk, and finally, finished or set.

Among the disadvantageous characteristics imparted to the fabric has been an excessive shrinking in one direction and substantially none in the opposite direction. Furthermore, the control of the preshrinking imposed upon the material was difficult to maintain, and incapable of producing a pre-shrunk fabric in which equilibrium conditions had been obtained. As a result, an unsatisfactory product resulted, having undesirable characteristics in that it was not uniform, or capable of retaining its preshrunk condition.

I have found that the shrinkage resulting from laundering operations is not due solely to increased crinkle which may be induced in the warp or weft yarns but that it is also due to a physical rearrangement and readjustment of the yarns and fibers due to the mechanical

working and reconditioning and flexing of the fabric in all directions while in its plastic condition during laundering. It is this rearrangement of the warp and weft yarns which I obtain by mechanically working the web rapidly and positively.

My process for preshrinking is preferably carried out after the usual preliminary steps, such as singeing, removing the warp sizing, bleaching, dyeing, printing, mercerizing, drying, calendering and polishing, or other customary operations have been performed upon the web so that no subsequent operation is necessary which might impair the full advantages of the preshrunk condition attained.

In accordance with the present invention the treated fabric is first rendered plastic by moistening it, or preferably, by passing it through a sizing solution in which a final sizing is imparted to the fabric and as a result of which the web is rendered soft and plastic in preparation for the subsequent steps of my preshrinking process. The web is then stretched weftwise to approximately the width desired in the final preshrunk fabric and then, while its surface is restrained to prevent formation of undulations therein, the web is forced by mechanical working and rearrangement of the component yarns, both warp and weft, into a contracted and reconstituted condition of equilibrium in which it is substantially immune to further contraction and rearrangement due to the wetting and working of subsequent laundering operations. Following the mechanical working of the web it is set and dried while fully supported in its passage from the working zone to and through the drying apparatus to prevent the imposition of warp tension thereon that might diminish the preshrunk condition attained by mechanical working of the web.

One of the primary objects of my invention is to overcome the disadvantages of earlier processes and obtain a preshrunk fabric which is capable of retaining its preshrunk condition in subsequent laundering operations.

Another object is to provide apparatus that is relatively simple to operate and which may be readily adjusted and controlled to vary its effect upon the web to impose a preshrunk condition thereon as circumstances may require.

One feature of the invention resides in the provision of an endless sectional band, comprising parallel travelling portions of the cord or the like, engaging the surface of the web for

preventing undulations of its surface as it passes through and from the web-working zones.

Another feature resides in a novel arrangement of the cord comprising the endless band so that the selvage of the web is not marked, rumpled or crinkled as cord portions of the sectional retaining band is caused to engage and disengage the web.

Other objects and features of the invention will become apparent upon consideration of the following description and appended claims when read in conjunction with the accompanying drawings in which:

Figure 1 is a side elevational view in simplified diagrammatic outline of parts of a form of my preshrinking apparatus suitable for carrying out my process;

Figure 1a is a continuation of Figure 1 and shows other parts of the apparatus;

Figure 2 is a plan view with certain parts omitted to more clearly show the driving arrangements for the apparatus illustrated in Figures 1 and 1a;

Figure 3 is an enlarged view of the web comm-
25 pressing roll and part of the companion feed roll shown in Figure 1a;

Figure 4 is a sectional view on the line 4—4 in Figure 3;

Figure 5 is a view, partly broken away, along the line 5—5 in Figure 1a;

Figure 6 is a fragmentary view taken along the line 6—6 in Figure 1a;

Figure 7 is a diagrammatic outline of a modified form of one part of my apparatus.

Referring now more particularly to the drawings, there is indicated by the dotted line 10 the centre line of a fabric or web which it is assumed has previously been subjected to processing, such as bleaching, dyeing, printing, calendering, etc., or combinations thereof. The web is drawn from a truck or bin 1 over an idler roll 2 into a cleaning device. In this cleaning device the fabric passes between brush rollers 3 which remove dust, lint, loose threads, etc. from the surfaces of the fabric web, this matter being carried away by a suction duct 4. From the cleaning device the web is drawn over an idler roll 5 to a sizing apparatus comprising a vat or trough 6 containing a suitable sizing solution and provided with an idler roll 7 and presser rolls 8, 9. The presser rolls may be driven by the main driving motor 11 for the apparatus. The drive passes through suitable speed regulating mechanism such as a Reeves "variator" as indicated at 12 in Figure 2 and passes to the rolls by means of a chain 13 operated from the variable speed shaft 14 of variator 12.

In passing through the sizing solution, which may be of starch, dextrin, gums or soluble oils 60 customarily used in finishing operations, the web is moistened and converted into a plastic, soft condition so that it may be readily worked upon in passing between a "compressing" roll 30 and a feed roll 31, Fig. 1a, to which it is directed 65 after passing through a tensioning frame 20 and over apparatus 40 for stretching the web weft-wise. The stretching apparatus is, preferably, positively driven from the constant speed shaft of variator 15 by a chain 41. The tensioning frame 20 has fixed guide rolls 21, 22 and an intermediate movable compensator roll 23 that acts to take up slack in the web, the weight of roll 23 acting to stretch all the goods to substantially the same degree so that goods of

uniform tension and stretch are fed to the weft-wise stretching apparatus 40.

Tensioning frame 20 is also provided at one side thereof with a pair of fixed sprocket wheels 24 and an associated endless chain 25 to which one end of the shaft of compensator roll 23 is connected. This sprocket and chain arrangement is duplicated at the other side of the tensioning frame so that lowering or raising of either end of the shaft of roll 23, as web slack accumulates or is taken up, results in driving the chain 25 to effect a corresponding movement of the other end of roll 23. In this way the roll 23 is maintained on an even keel to assure proper guiding of the web and obviate sidewise skewing thereof.

The shaft 26 which carries the lower sprocket wheels 24 is also provided with an additional sprocket wheel 27 acting through a chain 28 and sprocket wheel 29 to move the control member 17 of the variator 12 inwardly or outwardly when roll 23 moves upwardly or downwardly, respectively, suitable mechanism being provided for converting the rotary motion imparted by chain 28 into an axial movement of the member 17. The inward or outward movement of the control member 17, in response to the movement of roll 23 as slack is taken up or accumulates, causes relative axial movement of the discs 18 of the variator. This results in an increase or decrease in the effective diameter of the pulley like member formed by the discs 18 of the variator with respect to the constant speed pulley thereof in such manner that the associated belt or chain 19 drives the variable speed shaft 14 of the variator at an increased or decreased speed for speeding up or slowing down the operation of the driven roll 9 of the sizing apparatus as web slack is taken up or accumulates. Thus, the movements of the compensator roll 23 of tensioning frame 20 automatically regulate the speed of operation of the sizing apparatus 8, 9 with respect to the rate of operation of the apparatus 40 for stretching the web weft-wise and the compressing and feed rolls 30, 31.

I have shown the web after passing over the roll 22 of the tensioning frame 20 as being brought into contact with the expander 40 for stretching it weftwise. This step will not necessarily always be found essential to the process as will be pointed out later. I have indicated in Figures 1 and 2 the use of curved expander rolls 42, 43, 44, the outermost portions of the curve of each of these rolls being indicated by the reference characters 42a, 43a, and 44a respectively. I have indicated the web 10 by its center line as passing over the outer portions of the curve of these rolls. Other types of stretching devices may be used in place of these expander rolls, such as, for example, driven or undriven belt expanders or driven edge gripping rolls acting as expanders.

From the delivery end of stretching apparatus 40 the web passes to compressing roll 30 and feed roll 31, Fig. 1a, around which is directed an endless band 92 that forms a working surface against which roll 30 acts for compressing the web. An endless blanket 38 also directed around roll 31 and guide roll 39 supports the band 92 in its passage from rolls 30, 31 to a set of drying cans 93 with which band 92 cooperates as will later be described. The drying cans 93 are driven from variator 12a at the same rate as roll 31 by a chain 95.

The lower roll 31 is driven from the variable

speed shaft 14a of the main variator 12a by means of a chain 16. The constant speed shaft 15 of variator 12, from which expander rolls 42, 43, 44 are operated, also is driven by the variable speed shaft 14a of variator 12a through a chain 86 so that the feed roll 31 is operated at the same speed as the expander rolls, thus minimizing warp tension. The main variator 12a is similar in construction to the variator 12 described above and its constant speed shaft 15a is driven by motor 11 through a chain 87. Thus, the basic speed of the entire apparatus may be regulated by adjustment of the control member 17a of main variator 12a to regulate the rate of operation of the variable speed shaft 14a thereof by motor 11.

The compressing roll 30 shown herein, is similar to one of the several forms described in my earlier application and, as illustrated in Figures 3 and 4, is made up of a plurality of closely-positioned, thin, toothed discs 32 and intermediate spacers 33 fitted upon a shaft 34 and pressed tightly together thereon. The spacers 33 of roll 30 are slightly smaller in diameter than the discs 32 and thus provide shallow channels between the discs. The discs 32 may be made of stainless steel and the teeth 35 thereof are preferably relatively fine, pointed at their ends, beveled on the sides and slightly undercut to permit ready penetration of the cloth web and yarn components, or at least firm gripping thereof without injury or tearing upon entry and withdrawal.

The upper or compressing roll 30 is also positively driven but at a higher speed than the roll 31. Roll 30 may be driven from the variable speed shaft 14a of variator 12a through suitable speed adjusting mechanism to permit the ratio of the speeds of rolls 30, 31 to be readily varied, as desired. As illustrated herein, the shaft of roll 31 is provided with a gear 71 which actuates intermediate gearing 72 to drive a gear 70 on the shaft 34 of roll 30. The gear 70 is of the change gear type being removable to permit substitution of other gears for obtaining a desired ratio between the speeds of rolls 30 and 31.

I also utilize, in conjunction with compressing roll 30, a multi-part retaining band 45, extending from roll 30 to a roll 46, positively driven by the chain 47 at the same surface velocity as roll 31 and drier band 92 and positioned to cause the band 45 to travel parallel to band 92 and in closely spaced relation thereto so as to confine the web between it and the band 92 during the passage of the web through the compressing and retaining zone. Referring also to Figure 5, the retaining band 45 which is at least as wide as the web, comprises a pair of continuous cords 48, 49 made of any tough material not unduly softened by wetting and having good wearing qualities. Each cord passes a number of times, in contiguous parallel portions, through the shallow grooves between the discs 32 of roll 30 through corresponding aligned peripheral grooves in roll 46, and over rolls 50, 51 of a cord cleaning device 52. Each of the pair of cords also passes in a single reach around tensioning devices 53, 54 individual thereto.

In order that the arrangement of the pair of cords comprising band 45 may be clearly understood, the various passages of one of the cords will be described in detail. The cord 48 for example, extends downwardly in a single reach 48a from the fixed idler roll 55 of its tensioning device 53 into the outermost groove in the left-

hand half of compressing roll 30, into retaining contact with the upper surface of the web and into the outermost groove at the left of roll 46. From the roll 46, cord 48 extends upwardly around an idler roll 56 and across the rolls 50, 51 of cleaning device 52, in frictional contact therewith. The rolls 50, 51 are positively driven in opposite directions and partially immersed in a cleaning bath which is constantly changed through inlet and outlet connections 57, 58 respectively, to the vat 59, so that the rolls 50, 51 rubbing against the cords of band 45, remove therefrom any sizing or lint, for example, which may have been picked up by contact with the web. Thus, the cords being continually cleaned are maintained free of an accumulation of sizing, for example, that might clog the grooves or teeth of roll 30. Further, they are thus kept in an evenly moist condition and their expansion or contraction, therefore, minimized.

Cord 48 then travels over idler roll 60 and thence downwardly to the second groove at the left of compressing roll 30, through the corresponding groove in roll 46 and thence again across the cleaning rolls 50, 51. The circuit of cord 48 around rolls 30, 46 and across the cleaning device 52 is repeated as cord 48 passes through successive grooves in rolls 30 and 46, the cord progressing inwardly from left to right until it has passed through all the grooves in the left half of roll 30. On leaving the groove 61 at or near the middle of roll 30, cord 48 passes through the corresponding groove in roll 46 and then upwardly in a single reach 48b to the fixed idler roll 62 of its tensioning device 53, without traversing the web-cleaning device 52. In addition to the idler rolls 62 and 55 tensioning device 53 comprises an intermediate fixed idler roll 64 and a pair of rolls 63, 65 carried by a member 66 provided with weights 67 which act to take up slack in the cord 48 and maintain it sufficiently taut so that its various parallelly travelling portions form a relatively rigid and firm sectional band. From roll 65 the cord 48 is again directed over idler 55 and downwardly again at 48a to the outermost groove at the left of roll 30 and the full circuit is continuously repeated.

The circuit for cord 49 is similar to that for cord 48 except that, in its downward reach 49a from the fixed idler 68, Figure 5, of its tensioning device 54, it initiates its passages through the grooves of roll 30 at the outermost groove in the right-hand half of the roll and progresses inwardly towards the left and, after passing through the central groove 61a, returns in a single reach 49b to its tensioning device 54.

From the foregoing it may be seen that, on passing to the compressing roll 30, the web 10 is gripped by the teeth 35 of the discs 32 of the roll that extends between the cords 48, 49 of band 45 which is brought into contact with the upper surface of the web. As the web and band 45 pass to the nip between rolls 30 and 31, the drier band 92 is brought into contact with the underside of the web so that, in passing through the zone of contact between the teeth of roll 30 and the band 31, the web is confined between the band 45 and band 92 so as to be carried forwardly without tension thereon. As a result of the higher speed of roll 30, the web, when gripped by its teeth, is carried forward at a faster rate than that at which it would be otherwise advanced by roll 31, the wetted surface of the band 92 permitting a slight slippage of the web 75

thereon. Thus, while band 45 bearing against the web and forming a web-restraining zone with the band 92 exerts a restraining force that acts to prevent flexing or crinkling of the surface of the web, roll 30 acts to force the web forward into the zone where it is confined between band 45 and band 92 and works the cloth to effect a mechanical readjustment of the component yarns. The teeth 35 of roll 30 on entering the cloth pass into and between the fibres of both warp and weft yarns tending to loosen them and exert a shoving action that positions the weft yarns more closely together and acts longitudinally of the warp yarns to shove them together into a fatter or thicker state, i. e. with increased diameters, with the result that the web is contracted or compressed warpwise. Thus, while the cord band 45 and drier band 92 form a retaining zone which prevents rumpling or crinkling of the surface of the web, the teeth of roll 30 act to compress the web warpwise by exerting a shoving action on the fibres of both the warp and weft yarns.

The two cords 48 and 49 of retaining band 45, extending in single downward reaches 48a and 49a, respectively, to grooves adjacent opposite ends of roll 30 become fully engaged therewith prior to contacting the upper surface of the web. In forming the contiguous, parallel-travelling sections 48 and 49 of the band, the cords progress inwardly toward the middle of the roll and, after making their last traverse between rolls 30 and 46 in any one complete circuit, the respective cords leave the roll 46 from a groove near the middle thereof. As a result of this arrangement, the selvages of the web do not become waved, crinkled or otherwise marked. At all points over its surface the web is fully and completely retained and no surface undulations are allowed to form. By removing the cords 48 and 49 from contact with the web at or near the middle of the web, no slack in the cords is present at the selvages to cause crinkling or marking of the edges of the web.

The web is carried forwardly from rolls 30, 31 between the bands 45, 92 which support and hold the web so that warpwise tension is not placed thereon and surface undulations inhibited. A plurality of spring fingers 36 carried by a transverse bar 37, Figure 6, extend beneath roll 46 between the cords of retaining band 45 and act to press the web and band 92 against a supporting roll 69. The restraining force exerted on the web 10 by fingers 36 and their positions relatively to roll 46 may be regulated by providing for adjustment of bar 37 as more fully disclosed in my copending application Serial No. 754,575, filed Nov. 24, 1934. The fingers 36 extend beyond roll 46 substantially into the nip of an idler roll 96 around which a second drier band 97 is directed into engagement with the upper surface of the web so that although band 45 in passing around roll 46 is drawn out of retaining contact with the web, the latter continues to be held against band 92 in such manner as to prevent undulations in its surface.

In passing over the heated drums 94 of drier 93 the web is supported by the bands 92, 97 and thus dried and set in its treated condition without being subject to further strain. After passing around an idler roll 98, at the end of the series of drying cans, the bands separate and the web is carried by one of them to an oscillating device 99 which folds the finished preshrunk fabric into 75 piles in the bin 100. Tensioning devices 101 and

102, similar to the tensioning device 20 illustrated in Figures 1 and 2, are provided for the bands 92, 97, respectively, and suitable guide rolls 103 and 104 direct the bands back to the rolls 31 and 96.

The speed regulating variators through which the several parts of my apparatus are operated from motor 11 permit a close regulation and control of the relative operating speeds of the several parts so that tension on the web may be minimized in order that the preshrunk conditions attained in the several stages may not be diminished as the web passes through the apparatus.

I preferably carry out my preshrinking operations as part of the finishing operation upon a 15 fabric, and although with certain conditions and types of fabric the operation may be carried out while the fabric is in a dry condition, I prefer to have it in a plastic condition. Plastizing the fabric permits it to be more easily adaptable to 20 the mechanical working which I impose upon it for effecting a rearrangement of the component yarns and fibres to thus attain a preshrunk condition in which the yarns are in a state of substantial equilibrium. While the fabric may be 25 processed in a wet condition resulting from some preliminary operation, or may be made plastic by merely moistening it, I have illustrated and described my preshrinking operation as commencing by passage of the fabric through the 30 sizing apparatus 6, 9 in which a final sizing is imparted to the fabric. As a result of this operation the fabric is rendered soft and plastic in preparation for the subsequent steps of my preshrinking process.

Upon delivery from the sizing apparatus, the web is drawn forwardly over the tension control apparatus 21, 23 by the weft expander 40. It is desirable to minimize tension on the web between these points, and as previously described, 40 this may be effected automatically by roll 23 or through adjustment of variator 12 by an attendant.

The rate of operation of the expander 40 may be varied and regulated by means of the variator 45 12a to take up the web from roll 22 at substantially its rate of delivery by rolls 8, 9 so that it is not subjected to warp tension in being carried forwardly by the expander rolls 42, 43, 45.

The web after passing between the control rolls 50 8 and 9 may be found to have the desired width in which case it can be delivered directly to the working roll 30. If, however, the web is found to have a greater width than desired, it may be reduced weftwise by imposing a tension on it 55 warpwise between the control rolls 8 and 9 and the working roll 30.

It is assumed herein that, as a result of being drawn out warpwise in previous processing operations, the weftwise dimension of the web has 60 been decreased, as is usually the case, and therefore, in its passage through the expander 40, I cause the web to be drawn out weftwise to approximately the width which I have found will be present in a fabric which has been properly 65 preshrunk in two directions. The tension of passing the web 10 through the equipment subsequent to plasticizing tends to impose a warp strain on the web and thus tends to straighten out the warp threads and induce a crinkle in 70 the weft threads. This results in a shrinkage weftwise of the web. The amount of such shrinkage weftwise I can control by means of my tensioning mechanism 20. I also can control this weft shrinkage by varying the differential in 75

surface velocities between the web feeding rolls 8 and 9 on one hand, and the toothed compression roll 30. For example, it is possible to drive the toothed working roll 30, which firmly grips the cloth, at such a speed as to make it pull 5 against the cloth delivered to it by the feed roll 8 and 9 over and above the normal warp tension on the web in processing. On the other hand, I can drive the rolls 8 and 9 at a greater 10 surface velocity than the roll 30 and thus minimize the tension on the web between these two points.

In this operation I preferably pass the web while still in its plastic condition over a weft stretching means 40 and remove that portion of 15 weft shrinkage which I desire. That is, I stretch the weft back to the desired width normally present in the final preshrunk materials. This 20 weft stretching should be carried out to deliver the web to the toothed compression roll at that width which I have found will be present in a fabric which has been properly preshrunk in two directions. For example, a yard of grey material 25 which had an original woven width of 31" may have a width of only 27" upon delivery to the size rolls 8 and 9. This would be due to the drawing out of the web warpwise by the preliminary operations carried out in processing. The 30 desired and proper shrunk dimensions, which can be determined by performing a normal laundering operation upon a sample piece of cloth, may be found to be 33" by 29½". Therefore, I draw out the web weftwise by means of the expander 40 to 29½" in width. The web is then 35 delivered immediately to the working roll 30 which rearranges the fabric to a warpwise dimension of 33" in length. The weft dimension is unaffected and remains at 29½". This is accomplished by always supporting the web until it 40 is in a final set condition for marketing and thus eliminating all warpwise tension.

There may be, of course, a certain loss in the weft of the material after its discharge from the expanding means 40 due to the warp tension 45 which must be imposed upon the material to pull it through such equipment if the latter is not driven. This loss can be taken care of by over-stretching in width an amount equal to the subsequent loss in width due to the warp tension. 50 For example, if the loss in width in transferring to the roll 30 is found to be about 5-10%, the fabric may be over-stretched an equivalent amount and thus a desired width of the web obtained on the supporting surface formed by band 92.

On leaving the expander 40 the web passes to the working zone between compression roll 30 and drier band 92, which is advanced by roll 31, and the web is preferably taken up at the working 60 zone at substantially its rate of delivery from expander 40.

As the web enters the nip between rolls 30 and 31, the teeth 35 of roll 30 come into contact with the web at an angle to its surface and are forced 65 into the web and penetrate its surface. The teeth are so small that they tend to operate not only upon the individual weft yarns but also actually enter between the fibres making up the warp yarns. As may be seen from the enlarged 70 view of the toothed discs 32 in Figure 3, the teeth move in an arc intersecting the plane of the web and enter and leave the latter at an angle to its surface so that they tend to pull and work on the component yarns. This operation causes 75 a loosening and readjustment of the yarns and,

in view of the fact that the roll 30 is travelling faster than the web is advanced by the band 92 that extends around roll 31, there is a consequent shoving together of the fibres of the warp yarns as well as a compacting operation on the weft 5 yarns that are gripped by the teeth. Inasmuch as this shoving and compacting operation is carried on while the sectional retaining band 45 holding the web against band 92 on roll 31 acts to prevent undulations in its surface, there is a 10 mechanical readjustment and repositioning of the component yarns of the web, as distinguished from a mere crinkling of the surface of the web, so that the web is actually compressed and contracted warpwise to a state approximating its 15 optimum preshrunk condition.

Since the web is carried forward to the drier between retaining band 45 and dried band 92, travelling at the same speed, it is delivered to the set of drying cans and advanced therethrough, supported by bands 92 and 97, without being subjected to any tension tending to detract from the full effect of the previous preshrinking operations. The rate of operation of the drying cans 20 25 94 and the feed roll 31 for the drier belt 92 is coordinated with that of compressing roll 30 as all are driven from shaft 14a of variator 12a.

In passing through the drier, the bands 92, 97 alternately contact the surfaces of the drums 94 and since the radius between the centre of a 30 drum and either band is slightly greater when the band is not in contact with the drum, due to the interpositioning of the other band, each of the bands is slightly flexed a number of times in passing through the drier. As a result of this 35 flexing, there is a sliding movement of the bands relatively to each other and the web which prevents the latter adhering to either band. In being dried between the bands 92, 97 the cloth web is compressed only when the bands are passing 40 around a can and in contact therewith. In passing from one drum to another, there is a space, though relatively small, in which the bands are free from contact with either roll and the compression between the two bands is negligible 45 so that the web, which is not under tension, is free at this point to either contract or expand naturally.

This natural contraction or expansion of the web in passing between the two supporting and 50 flexing bands 92 and 97 and around the drying cans 94 may be taken advantage of to effect a final controlled preshrinking step of my process to compensate for any slight over or under contraction or expansion either warpwise or weftwise resulting from mechanical working of the web in the antecedent preshrinking operations. Consequently, when delivered from the drying cans, after being set and dried therein, the web 55 has attained a preshrunk condition in which its component yarns are in a state of substantial equilibrium and immune to further contraction either warpwise or weftwise when the finished fabric is subjected to a subsequent laundering operation.

In Figure 7, I have shown a modification of my apparatus suitable for carrying out my preshrinking operation. The web 10 may be delivered from the weft stretching or expanding means indicated by the reference character 40a to the nip between a roll 30a and a roll 31a. The roll 31a corresponds generally to the feed roll 31 of Figure 1a and the roll 30a is preferably a roll similar in operation to the web-working roll 30. Also passing between these rolls is a supporting 60 65 70 75 80 85 90 95 100 105 110 115 120 125 130 135 140 145 150 155 160 165 170 175 180 185 190 195 200 205 210 215 220 225 230 235 240 245 250 255 surface 75 preferably of a type similar in operation to the supporting surface 45 of Figure 1a so as to permit the roll 30a to operate on the web through it. This supporting surface is driven similarly to band 45, and is carried by suitable guide rolls 76, 77, 78, one or more of which may be positively driven. The supporting surface 75 comprises an endless cord, as more fully described in my copending application, Serial No. 674,495 filed June 6, 1933, extending in a plurality of closely spaced, parallel reaches around the rollers 76, 77, 78 and between the rolls 30a and 31a. However, the supporting surface 75 may, if desired, consist of a pair of endless cords forming a sectional band, such as the band 45 described above in connection with Figures 1a and 3 to 6. The supporting surface 75 carries the web in contact with the roll 31a in the zone g. The surface 75 and the roll 31a, as in my previous modification, travel at the same surface velocity and the roll 30a travels at a somewhat greater surface velocity, depending upon the type of material being processed. Thus the cloth or web 10 is forced forward by the roll 30a faster than it is being carried away in the zone g. Also processing around the roll 31a is a band 79. This band 79 against which the web lies, may be of canvas, and supports it after its delivery from the zone g and carries it over a guide roll 80 which positions the canvas band and web 10 in close contact with the drying drum 81. The web is supported by the canvas band 79 and held in contact with the drying drum 81 until it is set after which it is delivered from the drum and passes around the idler rolls 82, while still supported by the canvas band 79, and is delivered to an oscillating means 83 which folds it in a bin 84. The band 79 is directed around a drying drum 85 by suitable idler rolls and continues back around the roll 31a. It will be noted that by means of this arrangement the web is continuously supported at all points until it is set and delivered in a dry finished condition into the bin. There is thus no loss in the preshrunk characteristics which have been imparted to it during its processing.

From the foregoing description it may be seen that due to the fact that the relative speeds of web delivering and take-up parts of the apparatus may be closely controlled and driven and regulated through adjustment of the several speed regulating variators 12, 12a either by an attendant or, if desired, automatically in response to the movements of tension controlling rolls, the web travels through my preshrinking apparatus without tension being imposed thereon as a result of its movement, except when it is actually desired to impose tension as part of my preshrinking process as mentioned above.

In carrying out my process, as described above, the web is first moistened and rendered plastic in a final sizing operation. The weft-wise dimension desired in the final preshrunk fabric is then obtained by a weft-wise stretching on the expander rolls or similar device. The web is then worked by a toothed compressing roll to effect a warp-wise contraction of the web approximating the optimum condition of the final preshrunk fabric. In passing from the compressing and contracting stage to and through the drying cans, where it is set and dried, the web is free of tension since it is continuously supported and carried by either one or two travelling bands. In passing through the drying cans the flexing and sliding of a drier band

relatively to the web causes the web to be maintained free from adherence to the band. While not compressed against the band in advancing from one drying drum to another the web is free to contract or expand naturally to a condition in which its component yarns are in a state of equilibrium and practically immune from contraction in laundering operations, if this state of equilibrium has not already been attained in the preceding preshrinking stages of my process.

Although I have described my process and apparatus in detail it will be apparent to those skilled in the art many changes and variations may be made without departing from the spirit of the invention and, therefore, it is my intention and desire to include all such changes and variations within the scope of the appended claims.

I claim:

1. An apparatus for imposing a preshrunk condition on a fabric web comprising; means for wetting the web whereby it is rendered plastic; web working means having a plurality of web-penetrating projections for gripping and working the web to readjust the positions of its component yarns and effect a warp-wise compression of the web; a feed roll closely adjacent said work-roll; an endless band directed about said feed roll and forming a working surface on which the web is supported and against which said working means operate in compressing the web; and means for drying and setting the web in its preshrunk condition, said band cooperating with said drying means to advance the web therethrough and continuously supporting said web in its passage from said working means to and through said drying means to preclude the imposition of warp-strain on said web for obviating diminishment of the preshrunk condition imposed on the web by said working means.

2. An apparatus for imposing a preshrunk condition on a fabric web comprising; means for wetting the web whereby it is rendered plastic; web working means having a plurality of web-penetrating projections for gripping and working the web to readjust the positions of its component yarns and effect a warp-wise compression of the web; a feed roll closely adjacent said work-roll; an endless band directed about said feed roll and forming a working surface on which the web is supported and against which said working means operate in compressing the web; means for drying and setting the web in its pre-shrunk condition; a band cooperating with said drying means to advance the web therethrough, said band extending about said feed roll and forming a working surface on which the web is supported with one surface in contact therewith and against which said working means operate in compressing the web said band continuously supporting the web in its passage from said working means to said drying means; a second band cooperating with said drying means to advance the web therethrough; and means for directing a said second band into engagement with the opposite surface of the web subsequent to its delivery from said working means, whereby said web is continuously supported as it is advanced to and through said drying means to preclude imposition of warp-strain on the web to obviate diminishment of the preshrunk condition imposed on the web.

3. An apparatus for preshrinking a fabric web comprising; means for wetting the web whereby it is rendered plastic; web working means

having a plurality of web-penetrating projections for gripping and working the web to re-adjust the positions of its component yarns and effect a warp-wise compression of the web; a feed roll means for drying and setting the web in its pre-shrunk condition; closely adjacent said work-roll; a band cooperating with said drying means to continuously support and advance to and through said drying means said 10 band extending about said feed roll and forming a working surface on which the web is supported with one surface in contact therewith and against which said working means operate in compressing the web; a second band cooperating with said drying means to advance the web therethrough; means for directing said second band into engagement with the opposite surface of the web subsequent to its delivery from said working means, whereby said web is advanced 15 through said drying means continuously supported by said bands to preclude imposition of warp-strain on the web and obviate diminishment of the preshrunk condition imposed on the web; and means disposed intermediate said 20 working means and said directing means for said second band for engaging the opposite surface of the web and holding it against said first band to prevent formation of undulations in the surface of the web as it is advanced from said 25 working means to said drying means.

4. In a fabric treating means for modifying the superficial dimensions of a fabric; gripping means for working within the body of the fabric, retaining means engaging opposite sides of the 30 fabric operating adjacent to and subsequent to said gripping means, and heated means for setting the fabric, one of said retaining means supporting the fabric continuously during its passage from said gripping means through said 35 fabric setting means.

5. In a fabric treating apparatus suitable for modifying the superficial dimensions of said fabric; rotating means for gripping and penetrating the fabric, fabric retaining means engaging opposite sides of said fabric and acting with and subsequent to said rotating means, and heated means for setting the dimensions of said 40 fabric, one of said fabric retaining means extending continuously from said rotating means into said heated means.

6. An apparatus for preshrinking a fabric web comprising; means for wetting the web whereby it is rendered plastic; web working means having a plurality of spaced rows of web-penetrating 45 projections for gripping and working the web to readjust the positions of its component yarns and effect a warp-wise compression of the web; a feed roll closely adjacent said work-roll; an endless band directed about said feed roll and forming a working surface on which the web is supported and against which said working means operate in compressing the web; a plurality of spaced members extending between the rows of web-penetrating projections on said working means 50 into engagement with the surface of said web and cooperating with said band to form a web confining zone in which surface undulations of the web are prevented; heated means for drying the web in its preshrunk condition; and means for 55 directing said band into cooperative relation with said drying means for continuously supporting said web in its passage from said working means to and through said drying means to preclude the imposition of warp-strain on said web for ob-

viating diminishment of the preshrunk condition imposed on said web by said working means.

7. In a fabric treating apparatus for modifying the superficial dimensions of a fabric; gripping means for working within the body of the fabric; and retaining means operating immediately subsequent and adjacent to said gripping means, operative to prevent surface flexure of said fabric delivered from said gripping means and acting to continuously support and confine said fabric; 10 and heated means for drying and setting said fabric while still retained by said retaining means.

8. An apparatus for treating a fabric web to impose a preshrunk condition thereon comprising; web-feeding means; web-working means positioned adjacent said feeding means and provided with a plurality of web-gripping projections; a pair of endless cords each having a plurality of contiguous sections extending through adjacent spaces intermediate said rows of projections on 15 said web-working means; and means for guiding said cord-sections for movement parallel to each other to form an endless, sectional, web-retaining band, said cord guiding means being positioned adjacent said web-feeding means for causing said 20 sectional band to travel parallel to and closely adjacent said web-feeding means for holding the web against the latter.

9. In an apparatus for treating a fabric web; a pair of rolls each formed with a plurality of 30 circumferential grooves, said rolls being positioned so that their grooves are in alignment; and an endless, travelling sectional band engageable with a surface of said web, said band comprising a pair of endless cords arranged to make a number of 35 circuits between said rolls through aligned grooves thereof, the respective bands commencing said circuits in grooves adjacent opposite ends of said rolls, subsequently progressing inwardly through successive grooves toward the middle of 40 said rolls and returning from central grooves in said rolls to the grooves at opposite ends thereof so as to continuously travel between said rolls in a plurality of parallel portions extending between aligned grooves in said rolls for forming contiguous, 45 parallelly-travelling sections of said band.

10. In an apparatus for treating a fabric web; a pair of rolls each formed with a plurality of circumferential grooves; and an endless, travelling, 50 sectional band associated with said rolls and engageable with a surface of said web comprising a pair of endless cords each having a plurality of portions extending in parallel relation between aligned grooves in said rolls to form contiguous, 55 parallelly-travelling sections of said band, the respective cords initially entering grooves adjacent opposite ends of one of said rolls prior to engaging the surface of said web, and in successive traverses between said rolls for forming said 60 band, progressing inwardly toward the middle of said rolls to finally leave said other roll from adjacent grooves at the middle of said roll to return to the outer grooves at opposite ends of said one roll.

11. In an apparatus for treating a fabric web; a pair of rolls each formed with a plurality of circumferential grooves; an endless, travelling, sectional band associated with said rolls and engageable with a surface of said web, said band 70 comprising a pair of endless cords each having a plurality of portions extending in parallel relation between aligned grooves in said rolls to form contiguous, parallelly-travelling sections of said band, the respective cords initially entering 75

grooves adjacent opposite ends of one of said rolls and, in successive traverses between said rolls for forming said band, progressing inwardly toward the middle of said rolls to finally leave said other roll from adjacent grooves at the middle of said roll to return to the outer grooves at opposite ends of said one roll; and individual slack take-up devices engaging the respective cords in their respective passages from the grooves at the middle of said other roll to the related end grooves of said one roll.

12. In an apparatus for treating a fabric web; a pair of rolls each formed with a plurality of circumferential grooves; an endless, travelling, 15 sectional band associated with said rolls and engageable with a surface of said web, said band comprising endless cord having a plurality of portions extending in parallel relation between aligned grooves in said rolls to form contiguous, 20 parallelly-travelling sections of said band; and means for cleaning the component cord sections of said band while the latter is in motion.

13. In an apparatus for treating a fabric web; a pair of rolls each formed with a plurality of 25 circumferential grooves; and an endless, travelling band associated with said rolls and engageable with a surface of said web comprising a pair of endless cords each having a plurality of portions extending in parallel relation between 30 aligned grooves in said rolls to form contiguous, parallelly-travelling sections of said band; and means for cleaning the component cords of said band while the latter is in motion, said means including a pair of oppositely driven rolls in frictional contact with said cords.

14. In an apparatus for treating a fabric web; a pair of rolls each formed with a plurality of circumferential grooves; an endless, travelling, 35

sectional band associated with said rolls and engageable with a surface of said web comprising a pair of endless cords each having a plurality of portions extending in parallel relation between aligned grooves in said rolls to form contiguous, 5 parallelly-travelling sections of said band; and means for cleaning the component cords of said band while the latter is in motion, said means including a pair of oppositely driven rolls in frictional contact with said cords and a vat containing a constantly changed cleaning fluid in which 10 said cleaning rolls are partially immersed.

15. In an apparatus for treating a fabric web; a circumferentially grooved web-working roll; a circumferentially grooved band operating roll; an 15 endless, travelling, sectional band associated with said rolls and engageable with a surface of said web, said band comprising a pair of endless cords each having a plurality of portions extending in parallel relation between aligned grooves in said 20 rolls, each portion of the respective cords initially entering grooves adjacent opposite ends of said working roll to pass to the corresponding grooves in said band roll and progressing inwardly through successive grooves in said rolls toward 25 the middle thereof to form contiguous, parallelly-travelling sections of said band, the respective cords passing from the grooves at the middle of said band roll to return to the related grooves at 30 opposite ends of said working roll; means on said working roll extending between the several sections of said band for gripping and working said web; and means for cleansing each portion of the respective cords subsequent to contacting said web in traversing aligned grooves in said rolls and 35 prior to again contacting said web in traversing the next successive grooves in said rolls.

HENRY A. WOODHEAD.
